PROTECTION AGAINST BULLET SPATTER

Willard E. Swift, Jr., Worcester, Mass.

Application February 18, 1943, Serial No. 476,362

1 Claim. (Cl. 109—78)

(Granted under the act of March 3, 1883, as
amended April 30, 1928; 370 O. G. 757)

1

The invention described herein may be manufactured and used by or for the Government for governmental purposes, without the payment to me of any royalty thereon.

This invention relates to the prevention of damage caused by bullet splash or spatter entering crevices and openings through the walls of armored structures such as combat tanks and the like.

Bullet splash or spatter is the phenomenon that occurs when small arms fire strikes an armored surface. Particles of the outer shell and inner core of the bullet are thrown in all directions laterally from the point of impact. At least some of these particles skim along the surface and enter any opening in line with the surface. Moreover, on striking another surface, the spatter is again deflected in all directions, although with diminished force. Consequently, the bullet spatter may be deflected into openings and will pass through to the interior of the structure. This action occurs even if the opening follows an irregular path having right angle or obtuse angle turns, because of the deflection of the spatter on striking any obstructing surface.

Within a tank, for example, the entering spatter may cause injury to personnel or may damage some of the internal installations such as tubing and electrical cables. If the spatter enters between relatively movable parts, such as a gun rotor and its housing, it may wedge itself between the parts or may raise a burr on one of them, in either case immobilizing the movable part.

The invention resides in providing various means for deflecting the spatter either at an intermediate point in its path or at the end of its path through the opening, immediately before it enters the interior of the armored structure. The various forms of deflecting means can be best selected and applied after an understanding of the behavior of bullet spatter, and for this reason the phenomenon is discussed to some extent herein.

The invention is based largely on the discovery and analysis of the distribution of the spatter. As a result of such observations, I have found that a number of deflecting surfaces introduced in the path of the spatter will progressively reduce its momentum until it loses its damaging effect. Another construction based on these observations is the provision of a concave surface presented to the path of the spatter and extending through approximately 180 degrees, so that the direction of the spatter is substantially reversed. Where such a construction becomes too expensive or is

2

otherwise impracticable, a float deflector may be inserted in the path or at the end thereof, secured to one of the walls of the opening and forming with this wall an acute angle facing the incident end of the opening.

The underlying theories of the invention are illustrated schematically, and some illustrative embodiments are shown in the accompanying drawings in which:

10 Figures 1 to 13 inclusive are schematic illustrations of the behavior of bullet spatter under various conditions described below;

Figures 14 and 15 are detail sections of a tank turret having spatter protection for the sight opening;

15 Figures 16 to 20 inclusive are detail cross sections of various armored structure equipped with spatter protection devices;

Figure 21 is a detail cross section of a door structure showing a different form of trap for the crack;

Figure 22 is a detail section of a door or other structure presenting an opening, with spatter deflecting surfaces formed in the opening;

20 Figures 23 and 24 are detail sections of a gun rotor with a spatter trap beyond the clearance;

Figure 25 is a detail section of a gun rotor and housing with spatter traps in the clearance;

Figure 26 is a reproduction of Figure 23, illustrating the path of armor piercing fragments, and

Figure 27 illustrates a similar but shorter path and the insufficiency thereof.

Reference to these views will now be made by use of like characters which are employed to designate corresponding parts throughout.

By way of introduction it is pointed out that the spatter behaves in many respects like a fluid and follows substantially a fluid path on surfaces and in crevices. This will be observed throughout the detailed description.

Figure 1 illustrates normal incidence against a semi-hard flat surface 1. The bullet approaches along the arrow 2, and the spatter is distributed in all directions from the point of impact along the plane of the surface as indicated by the arrows 3. The bullet is a ball cartridge which does not penetrate the surface.

In Figure 2 an armor piercing projectile 4 has struck the member 5 and produced a similar pattern. The projectile has also formed a crater 6, the effect of which will presently be pointed out.

Figure 3 illustrates the impact at an angle of about 45 degrees to the member 1. The spatter

again radiates from the point of impact but the distribution is not uniform. It is about 20 per cent in the acute angle and about 30 per cent in the obtuse angle. A similar effect occurs at larger angles of incidence, such as 75 degrees to 80 degrees from normal, as shown in Figure 4. As the angle of incidence is increased, the point is eventually reached at which the projectile is not broken up but simply ricochets. The angle at which this happens is a function of the velocity of the bullet, the type and smoothness of the surface, and probably the design of the bullet.

The spatter pattern on face hardened surfaces is similar to that on semi-hard surfaces except where the surface is chipped by armor piercing fire.

Figures 5 and 6 show characteristic patterns when the plate is chipped or when the armor piercing core of the bullet is broken. Where this happens, the bullet spatter from the jacket or shell is somewhat similar to that produced by ball ammunition, skimming along the plate 10 as indicated by arrows 11. However, the core fragments and particles of the plate, indicated by the numeral 12, fly off in a haphazard manner. It might be noted here that an armor piercing core is quite likely to shatter on striking a semi-hard surface 13 at an angle as shown in Figure 6 but would not do so with a normal hit.

Figure 7 shows the effect of a bullet striking a hard, convex surface 15 at normal incidence. Whether the surface is cylindrical or spherical, the spatter is distributed in a plane tangent to the surface at the point of impact, as indicated by the numeral 16. This is true even if the incidence is not radial, as indicated by the numeral 17. Armor piercing ammunition on a hard surface, where the core or plate is shattered, does not follow this rule. Softer targets are discussed below.

Figure 8 shows the spatter distribution resulting from an impact of ball ammunition on a hard, concave cylindrical surface 18. The spatter radiates from the point of impact as for any other hard surface, but is deflected by the adjacent curved surface and is substantially reversed in direction if the total curvature of the surface approaches 180 degrees. Centrifugal force causes the particles to hug the surface of the plate. The concave surface is one of the most useful means of spatter control if it can be economically incorporated in the construction.

Figure 9 illustrates deflection of spatter at an intercepting surface. The spatter radiates along the first plate 20 in the manner described. A portion striking the nearby angularly disposed plate 21 again radiates from the point of impact. Due to this behavior, some of the spatter entering a jagged path will emerge at the other end of the path. The velocity is of course reduced with each impact.

On softer surfaces, such as cast armor and soft homogeneous plate where ball ammunition produces more or less of a crater, the spatter pattern is influenced by that crater. The spatter distribution on cast armor plate 25 of about 300 Brinell is shown in Figure 10 and on cold rolled steel plate 26 in Figure 11. The direction of spatter is approximately a prolongation of the wall of the crater, and the smaller the included angle, the narrower is the pattern. Thus, there is less danger when a crater is formed, since a greater portion of the spatter is thrown away from the plate.

Figures 12 and 13 show spatter from a soft convex surface 27 and from a soft concave surface 28. The direction of the spatter is not materially influenced by the shape of the surface.

Figure 14 shows the turret 30 of a tank having a sight opening 31. In an unfavorable design, this opening would be approximately in the upward projection of the sloping front plate 32, since the spatter would be directed towards the opening. Figure 14 shows the plate 32 disposed at such an angle that its projection lies considerably above the opening 31.

However, where a less favorable angle cannot be avoided, one or more angle irons 33 are secured across the front plate, as shown in Figure 15. These irons obviously deflect the spatter before it reaches the sight opening. If any spatter should travel beneath the first angle iron, it will be stopped by the second iron.

Figure 16 shows a door 40 closing against a wall or plate 41, leaving an angular crack 42. Reference to Figure 9 shows that a hit on the wall would spatter through the crack. A deflecting bead 43 near the entrance end of the crack is useful on hard plate, throwing the surface spatter upward.

The treatment of a direct hit at the entrance of the crack is shown in Figure 17 where a door 44 similarly closes against a wall or plate 45, leaving an angular crack 46. A deflector in the nature of a flat strip 47 is secured to one of the walls of the crack or a prolongation thereof, forming with this wall an acute angle facing into the direction of travel. Spatter entering such a trap loses most of its velocity because of the sharp angle of deflection and is relatively harmless on leaving the trap.

Figure 18 shows an improvement of this arrangement wherein the door is beveled off at 48 directly adjacent to the free edge of the strip 47. The beveled edge deflects the spatter back into the crack in cases where the spatter originated with sufficient energy to maintain velocity after entering the trap. Tests have shown that occasionally $\frac{1}{16}$ inch stock will be blown out by direct hits. Therefore, twelve gauge stock should be used and should be carefully welded in place. The sharper the turn made by the spatter, the more energy it loses in the turn. This applies also to curved deflecting surfaces.

Figures 19 and 20 illustrate the embodiment of a concave surface for deflecting the spatter back into the general direction of origin by bypassing or re-direction. In Figure 19 a door 50 closes against a wall or plate 51. A substantial space 52 is maintained between the parts, and a concave surface 53 is formed at the bottom of the space. Spatter from a direct hit at the entrance to the space is reversed or re-directed by the concave surface as shown by the arrows.

In Figure 20 two parts 54 and 55 are spaced to form a slit 56. A concave surface 57 formed on one or both of the parts adjacent to the slit throws the spatter across the slit. When the material is cast armor and produces fragments, or when armor piercing ammunition breaks up, a hit on a high point of the concave surface is likely to throw fragment into the slit. Where this is likely, a different treatment should be employed.

The application of the involute principle to a door is shown in Figure 21. A curved strip 58 is welded to the hull 59 at the emission end of the crack 60 between the hull and the door 61. Particles entering the strip are whirled and thus deprived of considerable momentum.

Where close tolerance is not required, the construction shown in Figure 22 may be used. The part 62 overlaps the part 63 and is formed with a rather large concavity 64. Opposite this, the part 63 is formed with a smaller concavity 65. The effect of a hit at the entrance end of the space is illustrated by the arrows.

This construction is effective for ball ammunition but passes some fragments produced by armor piercing ammunition. It should therefore not be used without additional protection.

A practicable treatment of a curved path is shown in Figure 23, between a gun rotor 70 and its housing 71. The spatter travels around the curve and is held very close to it by centrifugal force. A simple trap 72 is secured to the housing and forming an acute angle facing into the direction of travel, serves to catch the spatter.

Closely machined tolerances are often used to eliminate spatter. These result in slow and expensive production and immobilization of the rotor from dust, dirt, rust and burring by small arms fire. An effective trap permits larger tolerances.

An alternative construction is shown in Figure 24 where the trap is in the form of an involute 73 having an angularly disposed end 74. The spatter entering the trap is forced into a circular or whirling movement which reduces the velocity.

Another arrangement for a rotor is shown in Figure 25. A number of strips 75 are secured at intervals to the housing, each forming an acute angle facing into the direction of fire. This arrangement is very effective in trapping all the spatter.

Figure 26 is a reproduction of Figure 23 to show the effect of armor piercing bullet fragments. The fragments rebound from the armor in paths designated by the arrows 80. Little or no spatter escapes. This view illustrates the fact that adequate protection may be obtained if sufficient curved surface is available. Otherwise some of the particles will escape, as illustrated in Figure 27. Here the housing 71' provides a shorter curved path than in Figure 26. At the end of

this path the fragments still retain sufficient velocity to escape with appreciable momentum, as shown by the arrows.

The foregoing illustrations and descriptions show that effective spatter traps can be built for practically all structures. Although the traps shown for gun rotors are not altogether effective against fragments from small arms armor piercing ammunition on direct hits, they undoubtedly have considerable value on less direct hits.

The effectiveness of the trapping within a rotor housing depends on the dimension of the clearance and the length of the curved path. The trapping is more effective in a longer path. Small clearances are likely to result in locking of the rotor, due to the wedging of particles therein and burring of the surfaces, which has the same effect. A clearance of $\frac{3}{8}$ inch is not sufficient to prevent locking in this manner, and a wider clearance is recommended for use in connection with a trap.

Various embodiments of the invention have been illustrated and described. It is to be noted that the particular construction to be used should be selected in view of the nature of the apparatus where it is to be installed and in the light of principles herein discussed. Adaptation of the trap structure, indicated by these principles, may also be necessary.

30 What I claim is:

A door joint comprising, in combination, a hatch member having a hatch way with an arcuate shaped recess on the inner side thereof, a hatch cover having an extending marginal portion for overlapping the marginal portion of the hatch in said hatch member when it is engaged therewith, the underside of said projecting overlapping portion receding into the arcuate contour of a recess in the outer side of said hatch cover, said arcuate shaped recess having the bottom side thereof in substantially the same horizontal plane with the bottom portion of the recess in the inner marginal portion of said hatch member.
